UNITED STATES PATENT OFFICE.

CHRISTIAN J. TOERRING, OF PHILADELPHIA, PENNSYLVANIA.

ELECTRIC-ARC LAMP.

SPECIFICATION forming part of Letters Patent No. 732,141, dated June 30, 1903.

Application filed June 25, 1902. Serial No. 113,082. (No model.)

To all whom it may concern:

Be it known that I, CHRISTIAN J. TOERRING, a citizen of the United States, and a resident of Philadelphia, in the county of 5 Philadelphia and State of Pennsylvania, have invented certain new and useful Improvements in Electric-Arc Lamps, of which the following is a specification.

My invention relates to arc-lamps of the 10 long-burning or so-called "air-tight" variety; and the principal feature of my invention consists of such a lamp embodying in its construction a set of slotted tubes one within the other, which communicate with the globe-space surrounding the arc. These tubes have 15 certain functions in the construction and operation of the lamp; but as these features of my invention as a whole can be better appreciated after the construction of the lamp is 20 understood I will now proceed to describe it.

In the drawings, Figure 1 is a side elevation of my lamp. Fig. 2 is a side elevation from the opposite side. Fig. 3 is a central vertical cross-section. Fig. 4 is a cross-section of the carbon-holder and clutch-tube. Fig. 5 is a cross-section on the line 5-5. Fig. 6 is a cross-section of the carbon-holder and attached parts. Fig. 7 is a plan of the clutch, and Fig. 8 shows the globe-holder.

30 The top plate A carries the terminals A² A³ and the porcelain insulator A', from which the lamp is suspended. Rigidly secured to the top plate A by means of the collar A⁴, having legs A⁵, is the slotted supporting-tube B, 35 through substantially the entire length of which runs the slot B', which gives it its name.

To the lower end of the slotted supporting-tube B is rigidly secured in any convenient fashion the cap-plate C, having its lower surface ground off true to form an air-tight joint 40 with the upper surface of the small globe I, which may be made of glass and which has its upper surface ground off true to fit the under surface of the cap-plate to effect the 45 result stated.

Supported upon the cap-plate C and secured, if desired, to the slotted supporting-tube B is a casting C², upon which rests and to which is rigidly secured the magnet-supporting plate C³. Upon this magnet-support-

ing plate C³ are mounted the solenoids or magnets D in any well-known manner. Coöperating with these solenoids are the cores D', secured to a cross-plate D² and in turn secured to but insulated from the rod D⁴ by 55 the nuts D⁸ in any convenient manner. In turn secured to the rod D⁴ is the link E³, which takes in orifices in the hood E⁴ of the dash-pot E. The piston E⁵ of this dash-pot is secured to a pitman E², which is pivoted to 60 a base E', rigidly secured to the slotted supporting-tube B; but manifestly the piston could be made movable and the hood stationary, this being a mere reversal. A chain E⁶ passes around and is secured to the surface 65 of the roller E⁷, which is supported upon the slotted supporting-tube B. The chain E⁶ is fastened to the hood of the dash-pot E⁴ at one end and to the slotted clutch-tube F at the other end. In practice its inner end is made 70 much longer than shown. This clutch-tube F is supplied with a longitudinal slot F', extending through nearly its entire length, and has secured to its bottom in any convenient manner an arm F² and a bracket F³. This 75 arm F² may be integral with the tube F, as shown, or it may be secured to a collar which embraces the lower end of the tube, so as to close a little more completely the opening between the tube F and the tube B. A collar 80 effecting a similar function is shown at F¹⁰ in Fig. 4.

Pivoted to the bracket F³ is the plate F⁴, provided with a weighted end F⁵ and with an annular ring-clutch F⁶, which is secured to 85 but insulated from the plate F⁴.

The tripping-plate H is supported at some distance below the cap-plate C. It is secured to but insulated from the cap-plate by the standards H' and H² at a sufficient distance below the cap-plate to permit the carbon-holder to come down between the tripping-plate H and the cap-plate C, so as to render the carbon-holder accessible at this point. This construction adds much to the 95 facility by which an old carbon can be removed from the carbon-holder and a new carbon be put in place.

The tripping-plate H coöperates with the clutch to tilt the clutch when the same comes 100

- in contact with the upper surface of the tripping-plate, throwing the clutch into a more nearly horizontal position and permitting the carbon to feed down in the manner well understood. This tripping-plate has an aperture for the passage of the carbon, and the outer diameter of the tripping-plate is nearly but not quite equal to the inner diameter of the globe I at the same point.
- 10 The arm H³, which carries the negative carbon at its lower end, is rigidly secured against the lower face of the tripping-plate and is insulated therefrom, but is electrically connected with the standard H² by screws and insulating-washers in a manner which need not be more particularly described.

On the inside of the slotted clutch-tube F slides the carbon-holder G, which is tapered, so that the carbon may more readily be retained therein, and which has an aperture G', so that broken or worn-out pieces of carbon can be removed by an instrument inserted through this slot. The carbon-holder G is rigidly secured to a rod G², through a slot in the upper end of which passes a transverse piece G³, which is rigidly secured to the rod G² by upsetting the metal of the upper end of the rod G² on a metal washer G⁵, which clamps the whole together. Rigidly secured to the transverse piece G³ at one end is the metallic ring G⁴, to which is secured or threaded at the other end a binding-post or current-terminal G⁶. It will be clear from the drawings that the bolt G² slides within the slotted clutch-tube F, that the transverse piece G³ passes through the slot F' of the slotted clutch-tube F, that the ring G⁴ moves on the outside of the slotted clutch-tube F, but on the inside of the slotted supporting-tube B, and that the current-terminal G⁶ extends through the slot B' of the slotted supporting-tube B to the outside of this tube, where it is readily accessible.

Coming now to the circuit connections, which are shown as of the series type, current may be supposed to enter the lamp at the binding-post A³ and to pass by the wire 1 to the windings of the solenoids D and through these windings to the cable 2. From this cable 2 the current passes to the terminal G⁶, the ring G⁴, the transverse piece G³, the bolt G², to the carbon-holder G', and thence to the positive and negative carbons. The current now passes up the arm H³, to the standard H², to the cable 3, thence to the ring 4, which slides upon the rheostat 5. This rheostat may consist of two porcelain cylinders secured to the under face of the cap-plate A in any suitable manner and may be wound with a helix of resistance-wire. From the ring 4 the current passes along the windings below it on one of the cylinders of the rheostat and thence by the wire 6 to the winding on the other cylinder of the rheostat and thence to the binding-post A². It will be manifest that the various parts of the lamp are insulated from each other in the usual manner, such insulation having

been shown in the drawings at the proper points and having been referred to at some portions of the above description, but being unnecessary to more particularly point out and describe in detail.

It is now well understood in the art that an arc-lamp which burns within a comparatively small globe which is substantially air-tight has a life very much greater than is possessed by lamps burning in larger globes having free access to the air. In fact, whereas the life of arc-lamps burning in globes which are not air-tight is but a few hours the life of these so-called "air-tight" lamps is from two hundred to two hundred and fifty hours and even greater.

Now I have discovered that the construction of lamp which I have described has all the essential properties of an air-tight lamp so far as the length of the life of the carbons and other desirable features of so-called "air-tight" lamps is concerned, and this despite the fact that air in small quantities can get to the globe and the arc therewith down through my slotted tubes and through the aperture in the tripping-plate and through the space between the tripping-plate and the globe. It is only necessary that the two slots in the two tubes be placed at an angle to each other and preferably at an angle of one hundred and eighty degrees or opposite each to the other. With such construction I have found that the life of my lamp is substantially that of the so-called "air-tight" varieties of lamp, and for this reason I may without confusion designate my lamp as an "air-tight" lamp. Furthermore, I find that the tripping-plate when placed below the cap-plate, as shown, has not merely the function of giving ready access to the carbon-holder when this holder is in its lowermost position, as above described, but has the further important function of acting as a chamber or reservoir for the heated air, which tends to maintain the high temperature of the arc, thereby increasing the life of the carbon. Should, however, the slots in the two tubes be in line, a draft would be established which would do away with this quality of the tripping-plate as a means for increasing the life of the carbon. It will be seen, therefore, that the two slotted tubes have a very important function in my lamp, which is enhanced by the tripping-plate and which function relates to the longevity of the carbon, and that these slotted tubes have the further function of permitting the cable which connects the upper-carbon holder with a current-supply to have its connection readily accessible without any difficulty, so that this cable or this connection can be repaired if it should become necessary.

Supposing that I use carbons one-half inch in diameter, I may say that for one-hundred-and-ten-volt lamps I use a central orifice in the tripping-plate through which the carbon passes which is five-eighths of an inch in diameter. With such dimensions the life of

my carbon will be from two hundred to two hundred and fifty hours. It is not advisable to make the life of these carbons in a one-hundred-and-ten-volt lamp any longer than this, since at the end of this time the deposit on the lower carbon from the upper carbon becomes very ragged, causing an unsteady burning of the arc when the life is extended beyond this. For a two-hundred-and-twenty-volt lamp the size of the central orifice in the tripping-plate may be decreased to nine-sixteenths of an inch, and the outer diameter of the plate may be increased to some extent to make the space between the tripping-plate and the inner surface of the globe I somewhat smaller. This will naturally make the life of the lamp longer than two hundred and fifty hours, which is not objectionable with a two-hundred-and-twenty-volt single-burning arc-lamp. In such lamps the deposit of carbon from the upper to the lower electrode is much less than is the case with a one-hundred-and-ten-volt lamp, and, in fact, this deposit rarely if ever grows to a point where it produces an unsteady burning.

I may say that the clearance between the outer circumferential face of the tripping-plate and the inside surface of the inner globe may be taken as one-eighth of an inch or even less.

From what has been said it will be seen that while I gain all of the substantial advantages of the so-called "air-tight" lamp and other important advantages in the accessibility of the current connection to the carbon I am not compelled to devise any special means for producing a substantially air-tight fit between the outer face of the positive carbon and the walls of the aperture through which it slides to get into the inner globe. In other words, I do away with one of the troublesome constructional features of other air-tight lamps.

I may now describe the U-shaped globe-holder for my inner globe. This consists of a U-wire J, having a foot J' in its center and being formed with spring-coils J² and eyes J³ at the ends of the U. The globe-holder is fastened to the cap-plate C by screws J⁴, passing through the eyes J³. In order to remove the globe, the globe-holder is swung aside upon the pivots J⁴, the foot J' being permitted to yield away from the bottom of the globe by the natural spring of the coil J². When the globe-holder is in operation, the spring of these coils J² serves to press the upper ground face of the globe into contact with the lower face of the cap-plate C to produce an air-tight joint therebetween. The coils J² are twisted into the arms of the U-wire, and the axes of the coils are at right angles to the arms of the U-wire, thus increasing the stiffness of the spring-holders in a downward direction and saving space by having the coils lie flat against the globe.

The mechanical operation of my lamp will be clear without much description. Current

being fed thereto, the solenoids D are energized to pull down the cores D' and to pull up the clutch-tube F, any sudden or jerking motion being obviated by the dash-pot E. The clutch-tube F on rising tilts and raises the ring-clutch F' to strike the arc. When in the operation of burning the arc grows too long, the consequent weakening of the current in the solenoids permits the clutch-tube F to descend and the end of the clutch-plate to strike the tripping-plate H. The clutch-plate being thrown into a more nearly horizontal position, the upper carbon is allowed to descend until the arc again reaches the proper length. The external casing and globe have not been shown.

In conclusion I may state that it is manifestly not necessary to have the clutch-tube a complete circle in cross-section so long as it is of sufficient circular extent to cover the slot in the supporting-tube sufficiently to prevent an objectionable draft from within the globe, and it is to be understood that I use the word "tube" in all my claims in the broad sense of a complete or of a partial tube. From this point of view my invention consists of the slotted supporting-tube in a long-burning arc-lamp and a shield extending over and beyond the slot, which shield in certain cases may be on the outside of the tube.

What I claim is—

1. A long-burning arc-lamp comprising a substantially air-tight globe, a set of slotted tubes, one within the other, having their slots at an angle, and a carbon-holder within the inner tube, substantially as described. 100
2. A long-burning arc-lamp comprising a substantially air-tight globe, a set of slotted tubes one within the other, having their slots at an angle, and a conical carbon-holder within the inner tube, substantially as described. 105
3. A long-burning arc-lamp comprising a substantially air-tight globe, a set of tubes, one within the other, each having a slot and the slots being angularly displaced, a carbon-holder within the inner tube and current-carrying devices extending from the carbon-holder through the respective slots, substantially as described. 110
4. A long-burning arc-lamp comprising a substantially air-tight globe, a set of tubes one within the other, each having a slot and the slots being angularly displaced, a carbon-holder within the inner tube, and a conducting-ring between the tubes electrically connected, through the respective slots, to the carbon-holder and an external terminal, substantially as described. 115
5. A long-burning arc-lamp comprising a cap-plate, arranged to support a substantially air-tight globe thereagainst, a tripping-plate secured therebelow, a slotted supporting-tube for the cap-plate, a slotted clutch-tube moving therewithin, the slots being angularly displaced, and a carbon-holder inside the clutch-tube, substantially as described. 125

6. A long-burning arc-lamp comprising a cap-plate, a globe secured in a substantially air-tight manner against its under surface and a tripping-plate, having a central aperture for the passage of the carbon and a diameter nearly that of the inside of the globe, secured below the cap-plate to constitute a hot-air space, substantially as described.
7. A long-burning arc-lamp comprising a cap-plate, a globe secured in a substantially air-tight manner against its under surface, a tripping-plate, having a central aperture for the passage of the carbon and a diameter nearly that of the inside of the globe, secured below the cap-plate to constitute a hot-air space, a slotted supporting-tube secured to the cap-plate, a slotted clutch-tube therewithin, the respective slots being angularly displaced, and a carbon-holder inside the clutch-tube, substantially as described.
8. A long-burning arc-lamp comprising a top plate, a cap-plate, arranged to support a substantially air-tight globe thereagainst, a slotted supporting-tube connecting them, a slotted clutch-tube inside the supporting-tube, the respective slots being angularly displaced, and a carbon-holder inside the clutch-tube, substantially as described.
9. A long-burning arc-lamp comprising a cap-plate arranged to support a substantially air-tight globe thereagainst, a magnet-supporting plate, a slotted tube supporting these parts, a slotted clutch-tube, the respective slots being angularly displaced, and a carbon-holder inside the supporting-tube, substantially as described.
10. An arc-lamp comprising a bracket supporting a dash-pot piston, a dash-pot hood connected to magnet-cores and a chain respectively, a roller over which the chain
- passes and a carbon-clutch connected to the other end of the chain, substantially as described.
11. An arc-lamp comprising a slotted supporting-tube carrying a magnet-supporting plate, solenoids thereupon, a dash-pot piston supported on the supporting-tube, a dash-pot hood connected to the solenoid-cores and to a slotted clutch-tube respectively, and a carbon-holder within the clutch-tube, substantially as described.
12. An arc-lamp comprising a top plate having a rheostat secured to its under surface, a cap-plate and magnet-supporting plate secured to the top plate by a tube, a magnet having its cores connected to a clutch-tube on the inside of the supporting-tube and a carbon-holder inside the clutch-tube, substantially as described.
13. A pivoted U-shaped globe-holder having spring-coils twisted in its arms the axis of the coils being at right angles to the arms of the U, substantially as described.
14. A U-shaped globe-holder having a foot for engagement with the bottom of the globe, eyes for pivoting it to the cap-plate and spring-coils twisted in the arms of the U, the axis of the coils being at an angle to the arms of the U, substantially as described.
15. A long-burning arc-lamp comprising a cap-plate, a slotted supporting-tube secured thereto and a shield over the slot to prevent draft, substantially as described.

In testimony whereof I have signed my name to this specification in the presence of two subscribing witnesses.

CHRISTIAN J. TOERRING.
